UNITED STATES PATENT OFFICE

JOHN E. ERICKSON, OF ST. PAUL, MINNESOTA

SKI-CUTTING MACHINE

Application filed April 11, 1929. Serial No. 354,339.

My invention relates to ski cutting machines, and an object is to provide a machine which will automatically cut into the upper surface of wooden slabs or blanks from which the skis are made, in such manner that the two end portions of the ski will be much thinner than the central portion whereby the ski is given the desired flexibility. Another object is to provide a machine of this character which may be readily utilized to thin the forward and rearward portions of skis having different lengths. Another object is to provide means for firmly holding the blanks while they are being cut in the manner indicated above by a rotary cutter so as to prevent chattering of the blank and consequent imperfect cutting thereof.

The full objects and advantages of my invention will appear in connection with the detailed description thereof, and the novel features of my inventive idea will be particularly pointed out in the claims.

In the accompanying drawings which illustrate a practical embodiment of my invention, Fig. 1 is a top plan view of the machine. Fig. 2 is a side elevational view thereof. Fig. 3 is a view on an enlarged scale in vertical section on the line 3—3 of Fig. 1. Fig. 4 is a view on an enlarged scale in vertical section on the line 4—4 of Fig. 1. Fig. 5 is a view in vertical section on the line 5—5 of Fig. 1. Fig. 6 is a view in vertical section constituting an extension for the left hand portion of Fig. 3. Fig. 7 is a view on an enlarged scale in vertical section on the line 7—7 of Fig. 1. Fig. 8 is a view on an enlarged scale in vertical section on the line 8—8 of Fig. 1. Fig. 9 is a view in transverse vertical section substantially on the line 9—9 of Figs. 3 and 10. Fig. 10 is a view in horizontal section on the line 10—10 of Fig. 9. Fig. 11 is a side elevational view of a blank from which the ski is formed.

Referring to the drawings, it will be seen that there is a main frame designated in general by the numeral 12 which carries the supports and bearings for the various parts of the machine. As best shown in Fig. 1, a pulley 14 on the shaft of an electric motor 16 is connected by a belt 18 with a

pulley 20 secured to a shaft 22. A pulley 24 secured to the outer end of the shaft 22 is connected by a belt 26 with a pulley 28 secured to a sleeve 30 rotatably mounted on a fixed shaft 31, as shown in Figs. 1 and 2. A pulley 32 secured to the outer end of the sleeve 30 is connected by a belt 34 with a pulley 36 secured to a sleeve 38 rotatably mounted on a shaft 40. A small gear 42 secured to the sleeve 38 meshes with a large gear 44 secured to a shaft 46. A small gear 48 secured to the shaft 46 meshes with a large gear 50 secured to the shaft 40. A small gear 52 secured to the shaft 40 meshes with a large gear 54 loose on the shaft 46. The gear 54 meshes with a still larger gear 56 secured to a shaft 58 as shown in Fig. 1. The belt 34 instead of passing directly from the pulley 32 to the pulley 36 is looped underneath a pulley 60 as best shown in Fig. 2, the pulley 60 being secured to one end of a shaft 62. A small gear 64 secured to the shaft 62 meshes with a large gear 66 secured to a shaft 68 as shown in Fig. 1. A pair of sprocket wheels 70 are secured to the shaft 70 near the end thereof opposite the end which carries the sleeve 38 as will be understood from Figs. 1 and 3. A pair of sprocket chains 72 are trained around the sprocket wheels 70 and around a pair of sprocket wheels 74 mounted in a support 76 carried by the front of the frame 12 as will be understood from Fig. 6. The bearings for the sprocket wheels 74 are provided with customary takeup devices 78. At intervals around the sprocket chains 72, a pair of links thereof are connected by cross plates 80 which are attached as shown in Fig. 9. By referring to Fig. 3, it will be understood that the cross plates 80 engage the rear ends of blanks B and feed these blanks under a rotary cutter 82 which will be referred to later. By referring to Figs. 3 and 9, it will be seen that trackways are provided by means of a longitudinal track member 84 secured to the frame as shown in Fig. 7 and which has two downwardly projecting members 86 connected by a web member 88 which constitutes a support for the blank B. The members 86 are hollowed out from their up-

per sides and have lateral grooves 90 which receive inward projections 92 carried by the links of the chains. In order to aid in holding the blank B down as it passes under the rotary cutter 82, pairs of rollers 94 and 96 are provided which are rotated counterclockwise as viewed in Fig. 3 and engage the upper margins of the blank B as shown in Fig. 1. The rollers 94 and 96 are rotated in the proper direction on account of their being secured respectively to shafts 98 and 100 which at their ends opposite the ends which carry the rollers are provided with gears 102 and 104 respectively which mesh with a gear 106 secured to the shaft 68. As will be understood from Figs. 4 and 5, the shaft 98 has a bearing in a member 108 pivoted at 110 while the shaft 100 has a bearing in a member 112 pivoted to the member 108 by a pivot 114. The free end of the member 112 is provided with an adjustable screw bolt 116, the lower end of which is adapted to rest upon a fixed portion of the frame. The rolls 94 and 96 are held down upon the blank by means of a rod 118, the upper end of which is attached to the member 112 and the lower end of which is pivotally attached to the intermediate portion of an arm 120 which at one end is pivotally attached at 122 and whose other end carries a counterweight 124. The shaft 22 instead of being mounted in bearings fixed on the frame, is mounted in movable bearings 126, 127, and 128 best shown in Fig. 7. The bearings 127 and 128 are carried by the rear portion of a casting 130, the forward end of which is pivoted on the fixed shaft 31 as will be understood from Fig. 1 and the forward end of which carries an adjustable screw 131 whose lower end engages the track at the side of the blank and prevents the casting from dropping too far as will be understood from Figs. 2 and 4. A member 132 is secured to the casting 130 by a screw bolt 134. By referring to Fig. 8, it will be seen that the bearing 126 is held in a clamp constituted by a split hollow portion of the member 132, the split portion of this clamp being held upon the bearing 126 by a screw bolt 136. Yoke members 138 and 140 extend around the bearing 126 at the two opposite sides of the member 132. A bolt 141 passing through the member 138 and screwed into the member 140 serves to rotatably support a roller 142 between these two members. A screw bolt 144 passing through the body portion of the member 132 and engaging in a recess in the yoke members provides for adjustment of the position of the member 132 when the screw bolt 136 is loosened. By referring to Fig. 3, it will be seen that the yoke members just referred to are carried by the upper end of an arm 146 whose lower end is connected by a pivot 148 to one end of an arm 150 whose other end is connected to a rod 152.

carried by the lower rear portion of the frame. By referring to Figs. 2 and 7, it will be seen that the bearing 128 has depending ears 154 to which the upper end of a rod 156 is pivoted. The lower end of the rod 156 is pivotally attached by a pivot 157 to one end of an arm 158 whose other end is connected to said rod. On account of the tie connection provided by the arms 146 and 150 and by the rod 156 and the arm 158, it will be obvious that the shaft 22 carrying the rotary cutter 82 will be caused to assume parallel positions as it swings up and down. 70

By referring to Fig. 2, it will be seen that a lever 160 intermediately pivoted at 162 to the frame 12 has a short arm which engages under the pivot 157 as best shown in Fig. 7, there being a counterweight 164 secured to the outer end of the long arm of this lever. The weight 164 partly counterbalances the shaft 22. Secured to an end of the shaft 58, there is a wheel 166 to the periphery of which an arcuate cam member 168 is detachably secured by means of screws as shown in Fig. 3. The length of the cam member 168 is varied according to the length of the blank which is to be cut. In the embodiment shown, this cam member extends about half way around the circumference of the wheel 166. For making longer skis, the length of the member 168 would, of course, be correspondingly increased. The distance between the abutment plates 80 carried by the sprocket chains is slightly greater than the length of the longest ski which may be desired. Referring to Fig. 3, in which the wheel 166 rotates in the direction indicated by the arrow, it will be seen that the upper end of the member 168 has a hump 170 which at this time by its engagement with the roller 142 will lift the cutter 82 from engagement with the blank B so that the front end of the latter will be left with a short uncut portion F as shown in Fig. 11. As soon as the roller 142 drops behind the hump 170, the cutter 82 begins to cut into the upper surface of the blank. The cam member 168 gradually increases in thickness toward its middle portion 172 and then gradually decreases in thickness toward its other end. The result is that the blank as shown in Fig. 11 has a middle portion M which is only slightly cut and has end portions P and P' which are cut quite thin, the line of cut into the upper surface of the blank being indicated by the dotted line. In order to assist in holding down the blank as it is being cut, a member 174 is provided for engaging the upper surface of the blank. The member 174 carries an offset portion provided with an adjustable screw 176 whose head is adapted to engage at the side of the track and prevent the member 174 from dropping too far. As will be understood from Figs. 4 and 5, the member 174 has a curved extended portion 178 having downwardly extending ears 180

75 80 85 90 95 100 105 110 115 120 125 130

mounted on a pivot pin 182. From the other side of the member 174, a stem 184 extends forwardly and carries a weight 186. In order to prevent chattering of the ski as it is leaving the cutter, the following mechanism is provided. The shaft 58 as before stated carries a gear wheel 56. To one face of this wheel, a cam 190 is secured as will be understood from Figs. 5 and 7. Resting against the cam 190, there is a roller 192 carried by the lower end of a lever 194 intermediately pivoted at 196 as shown in Fig. 5. The lower end of an arm 198 is also mounted on the pivot 196 and this arm is connected with the upper end of the lever 194 by a screw bolt 200 which is screwed into the arm 198 and passes loosely through the lever 194. A coiled spring 202 tends to hold the arm 198 away from the lever 194 as far as the head of the bolt 200 will permit. The upper end of the arm 198 is provided with a clamp 204 which holds a short rod 206. A finger 208 extends forwardly from the rod 206 and normally inclines upwardly as shown in Fig. 3. The cam 190 is arranged to come into contact with the roller 192 before the ski passes out from under the cutter 82. During this time, the finger 208 through the intervention of the spring 202 is held resiliently down upon the rear portion of the ski as shown in Fig. 5. An arm 210 secured to the rod 206 is provided with a hole 212 through which a bolt 214 passes loosely as shown in Fig. 4. When the finger 208 is moved down into the position shown in Fig. 5, its downward movement is limited on account of the arm 210 coming into engagement with the head of the bolt 214. By referring to Fig. 2, it will be seen that the belt 34 under working conditions is held taut by a belt tightener 216 of ordinary construction which is carried by a lever 218 provided with a catch adapted to engage in notches of a segment member 220. When the lever 218 is thrown toward the left from the position shown in Fig. 2, the belt 34 is loosened to such an extent that it will not transmit motion and at the same time a brake 222 carried by the belt tightener is thrown up against the pulley 60 so that the machine is stopped quickly.

The operation and advantages of my invention have to a large extent already been disclosed. The feeding chains are driven at a moderate rate of speed by the shaft 40 having a large gear 50 secured thereto and driven by a small gear 48. The rotary cutter 82 is driven at a high rate of speed by the shaft 22 to which it is secured, this shaft being driven directly by the belt 18 from the motor 16 running at a high rate of speed. The cam carrying wheel 166 is driven at a slower rate of speed synchronized with the speed of the feeding chains due to the fact that the shaft 58 of this wheel carries a large gear 56 which is driven by progressively smaller gears 54 and 52. By referring to Fig. 3, it will be un-

derstood that the cam member 168 carried by the wheel 166 is so shaped as to cause the rotary cutter 82 to rise and fall so as to cut the blank from which the ski is made on the dotted line shown in Fig. 11. In order to complete the ski, the thick forward end F is turned up and the thick middle portion M is provided with the customary footholding members.

In order to feed the blanks B to the rotary cutter, they are placed just ahead of one of the engaging members 80 carried by the feeding chains 72 while the engaging member is at the front of the machine as shown in Fig. 6. It will be understood that the length of these chains and the arrangement of gearing are such that the shaft 52 carrying the cam wheel 166 and the cam 190 will make the same number of rotations for each complete circuit of the chains as the number of cross plates 80. In the particular embodiment shown, there are three of the cross plates 80 and hence the shaft 52 and the cams carried thereby will make three rotations while the feeding chains are going around once and making one complete circuit. As previously indicated, the cam member 168 will be changed to take care of skis of different length. The cam 190, however, does not need to be changed since this cam comes into operation during the last portion of the cutting operation for each ski.

I claim:

1. A ski cutting machine comprising a rotary cutter, mechanism for feeding a blank under said cutter, mechanism for raising and lowering said cutter for thinning the forward and rearward portions of the blank, a pressure applying device adjacent the rear of said cutter normally held above the blank, and means for bringing said device into engagement with the blank as the rear portion thereof is passing from said cutter. 100

2. A ski cutting machine comprising a rotary cutter, mechanism for feeding a blank under said cutter, a cam carrying wheel for raising and lowering said cutter for thinning the forward and rearward portions of the blank, a gear secured to the shaft of said wheel for driving the latter, a pressure applying device adjacent the rear of said cutter normally held above the blank, and a cam secured to said gear for bringing said device into engagement with the blank as the rear portion thereof is passing from said cutter. 110

3. A ski cutting machine comprising a rotary cutter, endless feeding chains, a number of cross plates carried by said chains in spaced relation for engaging the rear ends of blanks and feeding the latter under said cutter, a cam-carrying wheel for raising and lowering said cutter for thinning the forward and rearward portions of the blanks, driving mechanism for the shaft of said wheel and for said chains which causes said wheel for 125 130

each complete circuit of said chains to rotate as many times as the number of said cross plates, a pressure-applying device adjacent the rear of said cutter normally held above the blanks, and a cam carried by the shaft of said wheel for bringing said pressure-applying device into engagement with the blanks as the rear portions thereof are passing from said cutter.

10 4. A ski cutting machine comprising a rotary cutter, endless feeding chains, a number of cross plates carried by said chains in spaced relation for engaging the rear ends of blanks and feeding the latter under said cutter, mechanism for raising and lowering said cutter for thinning the forward and rearward portions of the blank, a pressure-applying device adjacent the rear of said cutter normally held above the blank, and means for 15 bringing said device into engagement with the blank as the rear portion thereof is passing from said cutter.

20 5. A ski cutting machine comprising a rotary cutter, mechanism for feeding a blank under said cutter, mechanism for raising and lowering said cutter for thinning the forward and rearward portions of the blank, a pivoted finger adjacent the rear of said cutter, a lever, a spring connection between said lever and 25 said finger, and a cam which engages said lever and forces said finger resiliently into engagement with the blank as the rear portion thereof is passing from said cutter.

30 In testimony whereof I hereunto affix my
35 signature.

JOHN E. ERICKSON.
